UNITED STATES PATENT OFFICE.

JOSEPH H. PURSER, OF LOS ANGELES, CALIFORNIA, ASSIGNOR OF ONE-HALF TO
LINDSAY S. HALL, OF LOS ANGELES, CALIFORNIA

SELVAGE-LOOP RETAINER.

Application filed May 15, 1923. Serial No. 339,061.

To all whom it may concern:

Be it known that I, JOSEPH H. PURSER, a citizen of the United States, and resident of Los Angeles, in the county of Los Angeles and State of California, have invented new and useful Improvements in a Selvage-Loop Retainer, of which the following is a specification.

This invention relates to a device for producing a loose woven selvage upon a textile fabric during the process of weaving. In weaving fabrics, such as ducks, a selvage is formed which is more closely woven than the body of the fabric. This is due to the filling 15 yarn pulling the threads of the warp more closely against one another at the edges than within the body of the fabric. In rubberizing duck for use in the manufacture of tires, the duck at the selvage is too closely woven to permit the rubber to impregnate the fabric. The result is that the selvage remains unaffected by the rubber and must be cut from the goods. This results in a serious waste of material. In weaving the 20 fabric, the edge warp yarns are crimped due to the pressure of the filling thereon and are under a strong tension. This causes a weakening of the fabric.

The primary object of this invention is to 30 provide a loop retainer which may be attached to a power loom and will produce a loosely woven selvage, thereby increasing its strength and permitting rubberizing. Another object of this invention is to provide 35 a device of the character described which will hold the filling yarn at the beginning of the return movement of the shuttle and until it has passed completely through the shed.

These objects together with other objects and corresponding accomplishments are obtained by means of the embodiment of my 40 invention illustrated in the accompanying drawing, in which:

Fig. 1 is a perspective view of so much of a loom as is necessary to illustrate the mounting of my improved retainer thereon; Fig. 2 is an enlarged perspective view of my improved retainer, a fragment of the loom 45 being shown to illustrate its mounting thereon; Fig. 3 is a front elevation of the retainer; Fig. 4 is a perspective view showing the tip of the finger disposed within the loop of the filling in position to hold the 50 same; Fig. 5 is a side view of a fragment of

the retainer showing in full lines the retracted or released position of the finger and in dotted lines the advanced or holding position; Fig. 6 is a diagrammatic view showing a number of the warp yarns and the crimp 55 formed at the selvage by reason of the pull upon the filling in the course of weaving duck with the ordinary selvage.

Referring more particularly to the drawing and especially to Fig. 1, a side frame of 60 the loom is indicated by 10. Spanning the side frames is the arch 11. The loom beam upon which the warp is wound is indicated by 12, the yarn being passed therefrom over a back rail 13. The warp is passed through 65 the harness 14 and reed 15, over the breast rail 16 and about the sand rolls 17. The shuttle box is indicated by 18. Mounted upon the breast rail is a stop 19. The lay 20 supports the shuttle in its travel. The 70 usual temple is indicated by 21. The structure just described is a well known plain loom and the parts just described are essential portions of all looms. As the present invention is not dependent upon the particular details of any of the moving parts 75 other than those above referred to, the loom need not be further described.

The movement of the harness causes a shed 80 to be formed through which the shuttle containing the filling is thrown, first to one side and then to the other. Each time that the shuttle returns, a tension upon the outside warp is produced equal to twice the tension upon the filling within the body of 85 the fabric, the filling being looped about the end threads and pulled by the tension therein on both sides. The reed then beats the filling into place and thereby crimps the outside warp as indicated in Fig. 6. My loop retainer relieves the tension upon the filling 90 upon its return.

Pivotedly mounted at 22 upon the stop block 19 is a lever 23. Connected to a post 24 upon the lever is a tension spring 25. A 100 post 26 mounted upon the block limits the movement of the lever in the direction in which the spring tends to turn the lever. Secured to the lever upon the other side of the pivot point is an arm 27 to which is pivotedly connected an operating arm 28 for moving the lever against the action of the spring 25. This arm may be reciprocated by a cam or any other suitable mechanical movement. The lever is provided at its 105

upper end with an elongated slot 29 through which extends a bolt 30. The bolt is secured to the lever by means of nuts 31 on opposite sides of the lever. A wrist block 32 is loosely journaled upon the bolt 30 and has an extension 33. Secured to the extension 33 is the finger 34. The finger is provided with an elongated slot 35 through which bolts 36 are passed so that the projection of the finger from the wrist may be adjusted. There is enough clearance between the bolt and the wrist bearing to permit rocking in a lateral direction. The amount of rocking is limited by a yoke comprising a bracket 37, on which is mounted an adjustable loop 38. The filling yarn will pull the tip of the finger so that when the latter extends therethrough, the finger rests against one side of the yoke as shown in Fig. 3. The spring 39 tends to pull the finger in the opposite direction against the other side of the yoke. A support for the filling yarn comprises a bar 40 having a raised portion 41 so that the filling yarn may be looped thereabout for a moment. The device operates in the following manner:

The warp yarn is shedded by the harness and the shuttle *s* is thrown therethrough to carry the filling from one side to the other as indicated in Fig. 2. The filling rests upon the support 40 back of the shoulder formed by extension 41. At this time the operating rod 28 is in its lower position, the spring 25 having rocked the lever 23 until it had engaged the stop pin 26. Spring 39 holds the finger against the outer side of the yoke. The tip of the finger is below the filling. The picking-stick then throws the shuttle to the opposite side, the filling looping about the finger as shown in Fig. 4. The tension upon the filling causes it to slip off the extension 41 and to engage the tip of the finger as shown in Fig. 3. This causes the finger to be swung toward the edge of the fabric and against the inside of the yoke. Upon the shuttle reaching the opposite side, the operating arm 28 is raised thereby removing the tip of the finger from the loop formed by the filling and the reed coming forward 50 pushes the warp outwardly against the filling. The opposite side of the loom is provided with a similar motion operating in alternation with the one just described. The finger is held at the outside of its yoke, in order that when it is advanced toward the warp, it will not be liable to enter between the yarn. However, the filling can pull the finger close to the outside warp yarn.

The finger takes all of the tension of the filling at the outside edge and provides a small amount of slack, upon the finger being removed, the reed pushing the warp against the filling. The result is that a loose woven selvage is formed. Due to the looseness of the weave at the selvage, the

outside warp yarn requires a different length for a given length of the woven fabric than the inner warp yarn. For this reason, the outside yarns are fed from spools 42 mounted upon the arch. In the present instance, three spools are shown, although a greater or lesser number may be used depending upon the weight and texture of the fabric which is being woven.

What I claim is:

1. In a loom having a shuttle, a loop retainer comprising a finger disposed at the side of the warp and yielding supported against lateral movements, means to advance said finger to a position back of the filling so that the return of said shuttle will loop said filling about said finger and to withdraw said finger at the end of the return travel of said shuttle.

2. In a loom having a shuttle, a loop retainer comprising a finger disposed at the side of the warp and yielding supported against lateral movement, means to advance said finger to a position back of the filling so that the return of said shuttle will loop said filling about said finger, and means to withdraw said finger at the end of the return travel of said shuttle.

3. In a loom having a shuttle, a loop retainer comprising a finger mounted to be advanced to and to be retracted from the warp at the side thereof, said finger being mounted to have a lateral movement, means tending to hold said finger laterally away from said warp, means to advance said finger to a position back of the filling so that the return of said shuttle will loop said filling about said finger and to withdraw said finger at the end of the return travel of said shuttle.

4. In a loom having a shuttle, a loop retainer comprising a finger mounted to be advanced to and retracted from the warp at the side thereof, said finger being mounted to have a lateral movement, means tending to hold said finger laterally away from said warp, means to advance said finger to a position back of the filling so that the return of said shuttle will loop said filling about said finger, and means to withdraw said finger at the end of the return travel of said shuttle.

5. In a loom having a shuttle, a loop retainer comprising a finger mounted to be advanced to and retracted from the warp at the side thereof, said finger being mounted to have a lateral movement, resilient means tending to hold said finger laterally away from said warp, means to advance said finger to a position back of the filling so that the return of said shuttle will loop said filling about said finger and to withdraw said finger at the end of the return travel of said shuttle.

6. In a loom having a shuttle, a loop re-

- tainer comprising a finger mounted to be advanced to and to be retracted from the warp at the side thereof, means to adjust the projection of said finger, said finger being mounted to have a lateral movement, resilient means tending to hold said finger laterally away from said warp, means to advance said finger to a position back of the filling so that the return of said shuttle will 10 loop said filling about said finger and to withdraw said finger at the end of the return travel of said shuttle.
7. In a loom having a shuttle, a loop retainer comprising a finger mounted to be advanced to and retracted from the warp at the side thereof, said finger being mounted to have a lateral movement, means tending to hold said finger laterally away from said warp, an adjustable yoke embracing said finger to limit its lateral movement, means to advance said finger to a position back of the filling so that the return of said shuttle will 15 20
8. In a loom having a shuttle, a loop retainer comprising a finger mounted to be advanced to and retracted from the warp at the side thereof, means to adjust the projection of said finger, said finger being mounted to have a lateral movement, resilient means tending to hold said finger laterally away from said warp, an adjustable yoke embracing said finger to limit its lateral movement, means to advance said finger to a position back of the filling so that the return of said shuttle will 25 30 35 40

In witness that I claim the foregoing I have hereunto subscribed my name this 8th day of May, 1923.

JOSEPH H. PURSER.
